J. W. BECKMANN.
SOAP POWDER DISPENSER.
APPLICATION FILED FEB. 9, 1917.

1,266,195.

Patented May 14, 1918.

Inventor:
John W. Beckmann,
by his attorney,
Charles R. Scott.

UNITED STATES PATENT OFFICE.

JOHN W. BECKMANN, OF NEW YORK, N. Y., ASSIGNOR TO AUTOMATIC POWDERED SOAP DISPENSER COMPANY, INC., OF NEW YORK, N. Y., A CORPORATION OF NEW YORK.

SOAP-POWDER DISPENSER.

1,266,195.

Specification of Letters Patent. Patented May 14, 1918.

Application filed February 9, 1917. Serial No. 147,579.

To all whom it may concern:

Be it known that I, JOHN W. BECKMANN, a citizen of the United States, residing at Richmond Hill, L. I., in the city of New York, borough of Queens, in the county of Queens and State of New York, have invented a certain new and useful Improvement in Soap-Powder Dispensers, of which the following is a specification.

10 The invention relates to devices for supplying soap powder in the limited quantities required for toilet use in public lavatories and similar places, and the object of the invention is to provide a device of this 15 character which shall be simple in construction, easily manufactured and operated, and adapted to resist successfully the severe usage to which mechanism of this type is subjected, and also to maintain the clean 20 and tidy appearance desired in such service.

Another important object is to provide the dispenser with locking mechanism which while simple in construction and operation, is sufficiently complex to protect the 25 contents and prevent its removal by the user except in the small quantities delivered by operating the dispensing mechanism.

The invention consists in certain novel features and details of construction by 30 which the above objects are attained, to be hereinafter described and claimed.

The accompanying drawings form a part of this specification and show the invention as it has been carried out in practice.

35 Figure 1 is a side elevation of the improved dispenser.

Fig. 2 is a corresponding front view.

Fig. 3 is a vertical section taken on the line 3—3 in Fig. 2, and partly in elevation.

40 Fig. 4 is a similar view of the upper portion, taken on the line 4—4 in Fig. 1.

Fig. 5 is a horizontal section taken on the line 5—5 in Fig. 1, the parts below being shown in plan view.

45 Similar letters of reference indicate the same parts in all the figures.

The present improvement is based on Letters Patent to me for toilet powder containers, dated Aug. 1, 1916, No. 1,193,223, in 50 which is described a device designed to hold face or like powder and supply it upon a puff or the like in the small quantities desired for such purposes. The present invention is an adaptation of the same mechanism 55 to the dispensing of soap powder or the like.

A is the cylindrical container forming the body of the dispenser, having a funnel-shaped bottom A¹ terminating in a short nipple A². The body is supported in the desired relation to a wash basin, not shown, 60 by a bracket A³ secured to the body, or by other suitable means, and A⁴ is a tubular skirt or extension mounted on the under face of the bottom A¹ and surrounding the nipple A² to direct the discharge of powder 65 to the hand held to receive it.

Extending axially of the body is a vertically movable valve rod C guided at the upper end in a bridge D extending diametrically across the interior of the body, 70 and carrying at the lower end a conical valve C¹ adapted to match against the lower end of the nipple A² as a seat and control the passage therethrough. The rod is held normally in the elevated position with the 75 valve closed, by a spiral expansion spring F abutting at the lower end against the bottom A¹ and at the upper end against a split-key C² inserted in the rod. The latter is depressed to lower the valve and open the 80 passage, by an arm C³ extending radially from the rod below the valve C¹, through a slot a in the extension A⁴. The arm is provided with a thumb-piece C⁴ by which such downward movement may be conveniently 85 performed, and the downward movement is limited by a stop C⁵, shown as a split key near the top of the rod, striking the upper face of the bridge or guide D.

Thus arranged and the container supplied with soap powder, a downward movement of the thumb-piece and rod opens the passage through the nipple A² and permits a portion of the contents to escape through the extension A⁴, and on releasing the 95 thumb-piece the rod is raised automatically by the spring F and the valve again seated on the nipple. The spring also serves as a stirrer or agitator for the soap powder in breaking up lumps and preventing caking. 100

In a device of this character it is necessary to provide means for protecting the contents against unauthorized removal in bulk; this is accomplished by a cover G having an annular flange G¹ closely inclosing the open upper end of the container A, and a means for locking such cover in place. The means shown consists of a dog H pivotally mounted in a vertical position at h in the bridge, having a hook H² at the upper 110

end adapted to engage an annular conical flange or rim on a head G^2 at the lower end of a stud G^3 fixed at the center of the cover on the interior. The lower end of the dog, 5 H^1 , is drawn normally outward by a contractile spring H^3 thus presenting the hook H^2 in position to snap over the rim G^2 and hold it in such engagement when the cover G is applied. Thus engaged the cover G 10 may be rotated freely in either direction but is held against removal.

At the end of the bridge opposite the dog is a hole a^1 in the body concealed by the flange G^1 of the cover in which is a notch 15 g adapted to register with such hole when the cover is rotated to bring both into coincidence, and in the rod C is a corresponding orifice c extending diametrically through the rod and adapted when properly 20 presented to permit a wire M or other suitable implement to be thrust through the notch g , hole a^1 and orifice c against the dog H and by pressure force the dog back in opposition to the spring H^3 sufficiently to 25 disengage the hook H^2 from the rim G^2 ; while thus held the cover is free and may be lifted.

Upon the upper face of the bridge or 30 guide D is a tubular guide D^1 extending from the hole a^1 nearly to the rod C and serving to direct the wire M to the orifice c and facilitate the entrance of the wire when such orifice is presented opposite the 35 end of the guide. The orifice is preferably so located as to be thus presented in alignment with the guide tube at a point between the highest and lowest position of the rod so that the latter must be positioned at 40 exactly the right height before the wire can pass and the unlocking operation completed.

The slot a in the extension A^4 serves to hold the rod against rotation and thus insures the presentation of the orifice c to the 45 guide tube D^1 in axial alignment therewith.

I claim—

1. In a device of the character set forth, 50 a body, a bottom therefor having a valve-opening therein and an extension adjacent such opening and having a vertical slot, a guide in said body, a spring-actuated valve rod extending through such opening and bridge, a valve on said rod below and controlling such opening, an arm on said rod below said valve and extending radially therefrom 55 through such slot, cover-locking means, and cover-unlocking means controlled by said rod.

60 2. In a device of the character set forth, 65 a body, a bottom therefor having a valve-opening therein and an extension adjacent such opening and having a vertical slot, a guide in said body, a spring-actuated valve 70 rod extending through such opening and

guide, a valve on said rod arranged to control such opening by the axial movements of said rod, and an arm on the valve rod below the valve and bearing against the under side thereof, said arm extending radially and movable bodily with said rod and in said slot, said arm outside of said extension being provided with a thumb-piece, cover-locking means, and cover-unlocking means controlled by said rod. 75

3. In a device of the character set forth, a body, a bottom therefor having a valve-opening therein, and an extension adjacent such opening and having a vertical slot, a guide in said body, a spring-actuated valve 80 rod extending through such opening and guide, a valve on said rod arranged to control such opening by the axial movements of said rod, an arm on the latter below said valve and bearing against the under side 85 thereof and extending radially therefrom through such slot and adapted to reciprocate with said rod, a removable cover, means for locking said cover to said body, and unlocking means controlled by said rod. 90

4. In a device of the character set forth, a body, a bottom therefor having a valve-opening therein, a guide in said body, a spring-actuated valve rod extending through such opening and guide, a valve on 95 said rod below and controlling such opening, an arm on said rod below said valve adapted to reciprocate with said rod, a stop on said rod arranged to coact with said guide and limit the downward opening 100 movement of said rod and valve, a removable cover for said body, and means carried by said guide for locking said cover to said body, and cover-unlocking means controlled by said rod. 105

5. In a device of the character set forth, a body, a bottom therefor having a valve-opening therein, and an extension surrounding such opening and having a vertical slot, a bridge extending across the interior of 110 said body, a spring-actuated valve rod extending through such opening and bridge, a valve on said rod below and controlling such opening, an arm on said rod below said valve and extending radially therefrom 115 through such slot, a removable cover for said body, a spring-actuated dog pivotally mounted in said bridge, and a head on the interior of said cover arranged to be engaged by said dog. 120

6. In a device of the character set forth, a body, a bottom therefor having a valve-opening therein, and an extension surrounding such opening and having a vertical slot, a bridge extending across the interior of 125 said body, a spring-actuated valve rod extending through such opening and bridge, a valve on said rod below and controlling such opening, an arm on said rod below said valve and extending radially therefrom 130

through such slot, a removable cover for said body, a spring-actuated dog pivotally mounted in said bridge, a head on the interior of said cover arranged to be engaged by said dog, and an annular flange on said cover inclosing the upper end of said body and having a notch in its edge, said body having a hole located to register with said notch to admit means for disengaging said dog and head.

7. In a device of the character set forth, a body, a bottom therefor having a valve-opening therein, and an extension surrounding such opening and having a vertical slot, a bridge extending across the interior of said body, a spring-actuated valve rod extending through such opening and bridge, a valve on said rod below and controlling such opening, an arm on said rod below said valve and extending radially therefrom through such slot, a removable cover for said body, a spring-actuated dog pivotally mounted in said bridge, a head on the interior of said cover arranged to be engaged by said dog, an annular flange on said cover inclosing the upper end of said body and having a notch in its edge, said body having a hole located to register with such notch, and a guide-tube on said bridge extending from such hole toward said rod, the latter having an orifice therein arranged to be positioned in alinement with said guide-tube, hole, and notch to admit means to said dog for disengaging it from said head.

15 8. In a device of the character set forth, a container, a removable cover therefor, an endwise movable rod, a controlling valve carried by said rod, a pivoted latch engageable with the cover for holding the latter in locked position to prevent its removal, and means, operative only when said rod is in predetermined position, for moving said latch to permit removal of the cover.

20 9. In a device of the character set forth, a body, a bottom therefor having a valve-opening therein, and an extension surrounding such opening and having a vertical slot, a bridge extending across the interior of said body, a spring-actuated valve rod extending through such opening and bridge,

40 a valve on said rod below and controlling such opening, an arm on said rod below said valve and extending radially therefrom through such slot, a removable cover for said body, a spring-actuated dog pivotally mounted in said bridge, a head on the interior of said cover arranged to be engaged by said dog, an annular flange on said cover inclosing the upper end of said body and having a notch in its edge, said body having a hole located to register with such notch, 50 and a guide-tube on said bridge extending from such hole toward said rod, the latter having an orifice therein arranged to be positioned in alinement with said guide-tube, hole, and notch to admit means to said dog 55 for disengaging it from said head.

10 9. In a device of the character set forth, a container, a removable cover therefor, an endwise movable rod, a controlling valve carried by said rod, a pivoted latch engageable with the cover for holding the latter in locked position to prevent its removal, and means, operative only when said rod is in predetermined position, for moving said latch to permit removal of the cover.

15 10. In a device of the character set forth, a container, a removable cover therefor, an endwise movable rod, a controlling valve carried by said rod, a pivoted latch mounted in said container and engageable with the cover for holding the latter in locked position to prevent its removal, and means, operative only when said rod is in predetermined position, for moving said latch to permit removal of the cover.

20 In testimony that I claim the invention above set forth I affix my signature.

JOHN W. BECKMANN.
